(57) **ABSTRACT**

A bag carrying system having a removable handle and wheel assembly is provided. The system includes a bag having a back portion with a panel overlying the back portion and a handle and wheel assembly comprising a handle portion, a wheel portion and a longitudinally extending supporting element connected therebetween. Significantly, the longitudinally extending supporting unit of the handle and wheel assembly is designed to be placed between the panel and back portion of the bag for releasably attaching the assembly thereto.

FIG. 3

FIG. 4

FIG. 5

1

BACKPACK WITH REMOVABLE HANDLE
AND WHEEL ASSEMBLY

RELATED APPLICATIONS

This application is a Continuation of patent application Ser. No. 10/827,984 filed Apr. 19, 2004, now U.S. Pat. No. 7,036,641 which claims the benefit of Provisional Application No. 60/523,780 filed Nov. 19, 2003.

BACKGROUND

The present invention relates to luggage and bags, and more particularly to a backpack which may either be worn by using a pair of shoulder straps, carried by means of a handle, or wheeled along a surface by means of a removable handle and wheel assembly.

A recent development in the luggage and bag industry has been the use of wheeled baggage and bags. Luggage and bags of this type typically include a wheel unit and an extendable handle so that the user can pull the luggage or bag unit along a flat surface without having to bear the full weight thereof. Moreover, additional items may be supported along the bag or luggage in order to ease the burden of the use, for example, when moving through airports or along the city and suburban side-walks, or even for high school and college students walking between classes.

The most commonly available luggage or bag item of this type has wheels and an extendable handle permanently attached to the bag item. When the luggage or bag item is not being wheeled, the extendable handle is retracted. The disadvantage of this construction is the difficulty in carrying the luggage or bag since the weight of the wheel and handle assembly is often significant.

Accordingly, it would be desirable to provide a luggage or bag system consisting of a bag and a wheel and handle assembly which may be readily secured to the bag when needed and removed when not needed.

SUMMARY OF THE INVENTION

Generally speaking, and in accordance with the invention, a bag carrying system having a removable handle and wheel assembly is provided. The system includes a bag having a back portion with a panel overlying the back portion and the handle and wheel assembly comprising a handle portion, a wheel portion and a longitudinally extending supporting element connected theretwixt. Significantly, the longitudinally extending supporting unit of the handle and wheel assembly is designed to be placed between the panel and back portion of the bag for releasably attaching the assembly thereto.

In addition, the bag itself includes one or more engaging elements for selective coupling to the longitudinally extending supporting element of the handle and wheel assembly when the supporting element is disposed between the panel and back portion of the bag. The one or more engagement elements comprise one or more locking elements having either a rotating locking mechanism or a spring loaded locking mechanism.

In a preferred form, at least one locking element is located along the top portion of the bag and a second locking element is located along the bottom portion of the bag. These locking elements are designed to selectively couple to transversely extending trays that extend from the longitudinally extending supporting element of the handle and wheel assembly.

In one form, there are two trays extending from the supporting element of the handle and wheel assembly, one of which engages locking members along the top of the bag and a second which engages locking members along the bottom

2

of the bag. These trays are formed with one or more cut-outs that are designed for mating engagement with the locking members.

In its preferred form, the handle and wheel assembly of the invention includes one or more supporting rods that are connected between the handle portions and the wheel portions. The one or more supporting rods are tubular in form in order to telescopically receive corresponding length adjustment rods therewithin.

10 The inventive design is most applicable to a backpack, which normally includes a pair of shoulder straps each having first and second ends attached to the back portion of the backpack at locations therealong where the panel does not overly the back portion. This is achieved by having the overlying panel disposed between the attached ends of the straps.

15 In the preferred form, the panel of the backpack or other type of bag comprises a pivotal flat member that is secured along the back portion of the bag. The flap panel is releasably secured to the back portion of the bag by means of a conventional zipper mechanism.

20 Accordingly, it is an object of the invention to provide an improved bag carrying system.

Another object of the invention is to provide a bag carrying system having a removable handle and wheel assembly.

25 Yet a further object of the invention is to provide a bag carrying system comprising a backpack or other bag that can be both worn or carried as well as wheeled along a surface.

Still other objects and advantages of the invention will, in part, be obvious and will, in part, be apparent from the following description.

BRIEF DESCRIPTION OF THE DRAWINGS

35 For a fuller understanding of the invention, reference is made to the following description, taken in connection with the accompanying drawings in which:

FIG. 1 is an exploded perspective view of the inventive backpack and removable handle and wheel assembly combination;

40 FIG. 2 is a perspective view of a detailed portion along the top of the backpack, illustrating in one version of a locking unit used to releasably couple the handle and wheel assembly to the backpack;

45 FIG. 3 is a cross-sectional view taken along line 3-3 of FIG. 2;

FIG. 4 is a top plan view showing the locking unit depicted in FIG. 1 as it engages the upper platform of the inventive removable handle and wheel assembly;

50 FIG. 5 is a top plan view similar to FIG. 4 and illustrating engagement and locking of the locking unit to the upper platform of the inventive removable handle and wheel assembly;

FIG. 6 is a rear perspective view of the backpack and removable handle and wheel assembly combination of the 55 invention in which the removable handle and wheel assembly is disposed along the rear of the backpack and maintained therealong by a removable flap;

FIG. 7 is a cross-sectional view taken along line 7-7 of FIG. 6 and illustrates the lower platform that extends from the 60 inventive removable handle and wheel assembly engaging to the supporting legs of the backpack;

FIG. 8 is a cross-sectional view similar to FIG. 7 in which the supporting legs (spring-loaded) are pulled downwardly in order to release the lower platform of the removable handle and wheel assembly; and

FIG. 9 is a cross-sectional view taken along line 9-9 of FIG. 8

DETAILED DESCRIPTION

The inventive system includes a backpack 11 and a removable handle and wheel assembly 31, as best shown in FIGS. 1 and 6. Backpack 11 is made of a fabric-type material and includes a main compartment 13 accessible via a zipper 14 and a supplemental compartment 15 disposed along front panel 25 of compartment 13 and accessible by means of a zipper 16. Backpack 11 also includes a pair of shoulder supporting straps 19 fixed along the rear of the backpack and a reinforced carrying handle 17 fixed along the top of main compartment 13.

In FIG. 2 and FIG. 3, a locking unit 51 comprising a rotating knob 53, a rectangular lock member 55 rotatable by means of knob 53 and a screw 57 fixed therebetween is shown mounted on top 23 of compartment 13. Locking unit 51 is used to removably attach handle and wheel assembly 31 to backpack 11. One or more locking units of this type may also be formed along bottom 29 of main compartment 13. Alternatively, bottom 29, as shown best in FIGS. 6, 7, and 8, includes a pair of feet 21 affixed thereto by means of a spring loaded pin 61 about which a spring 63 is wrapped. This spring loaded mechanism enables each of feet 21 to be pulled downwardly away from bottom 29 of main compartment 13 so that removable handle and wheel assembly 31 can be selectively coupled to feet 21 as described below. This spring loaded mechanism may be used in place of locking unit 51 along the top of the backpack.

Referring again to FIG. 1, removable handle and wheel assembly 31 comprises metal or plastic support rods 33 extending between an upper platform 43 and a lower platform 39. Support rods 33 at the bottom ends thereof fit into wheel guard supports 37 in which wheels 35 are mounted. Extending from each wheel support 37 is platform 39 formed with a pair of cut-outs 41 used for selectively engaging feet 21 depending from bottom 29 of backpack main compartment 13 (see FIGS. 7-9). At the top of support rods 33 are a pair of platform supports 44 for enabling upper platform 43 to be supported. Platform 43 is formed with a forward notch 45 that is used for selective engagement with locking unit 51 (see FIGS. 3-5). Significantly, support rods 33 are formed with tubular openings therewithin (not shown) such that a pair of upper length or height adjustment rods 47 may be telescopically received therewithin. Rods 47 lead upwardly to a grooved handle 49, which is normally grabbed when wheeling backpack 11. Handle 49 may be disposed in an upper condition during wheeling and a lower condition in which rods 47 are telescopically received within rods 33 such that handle 49 is disposed at the same level as platform 43.

Importantly, the back of backpack 11, as best shown in FIG. 6, is formed with a cushioned panel flap 27 which selectively overlies the back of backpack 11. This enables removable handle and wheel assembly 31 to be disposed between the back of main compartment 13 and flap 27, which is closed by means of zipper 28. In this condition, handle and wheel assembly 31 is usable in conjunction with backpack 11. To remove assembly 31, zipper 28 is unzipped, upper platform 43 is disengaged from locking unit 51 and lower platform 39 is uncoupled from feet 21.

It will thus be seen that the objects set forth above, and those made apparent from the preceding description, are efficiently attained, and since certain changes may be made in the products set forth above without departing from the spirit and scope of the invention, it is intended that all matter contained

in the above description and shown in the accompanying drawings shall be interpreted as illustrative and not in a limiting sense.

It is also to be understood that the following claims are intended to cover all the generic and specific features of the invention herein described, and all statements of the scope of the invention, which, as a matter of language, might be said to fall therebetween.

The invention claimed is:

1. A bag assembly comprising:
a bag having a bottom portion with a bag supporting foot extending downwardly from said bottom portion; and a bag-holding assembly with a handle and a bottom member engaging and holding said bag on said handle; wherein when said bag is engaged by said bottom member, said bag supporting foot extends below said bottom member to form a support for said bag assembly; wherein said bottom member includes a plate attached to said handle, said plate being formed with an aperture, with said bag supporting foot extending through said aperture; and wherein said bag supporting foot includes a spring-loaded locking mechanism, said mechanism being movable to create an opening for selectively receiving and locking said bag to said bottom member after said bag supporting foot passes into said aperture.

2. The assembly of claim 1, wherein said bag further includes a top portion having a top locking member fixed thereon for selectively securing said bag to said handle.

3. The assembly of claim 1, wherein said bag has a bag top releasably secured to said handle.

4. The assembly of claim 3 further comprising an engagement member attached to said handle, said bag top being releasably secured to said engagement member.

5. The assembly of claim 1, wherein said aperture has a lateral opening sized and shaped to receive said bag supporting foot.

6. A backpack system comprising:
a frame having an elongated support with a handle at one end, a pair of wheels at the other end and a bottom member disposed adjacent to said bottom wheels; and a bag having two feet extending downwards and configured to support said bag on a flat surface, said frame being adapted to releasably engage and secure said bag on said bottom member;

foot attaching members for attaching said feet to said bag; wherein when said bag is engaged by said frame, said feet extend downwardly of said bottom member to support said bag and said frame on a flat surface; and

wherein each of said foot attaching members includes a pin attached to and extending downwardly from said bag, each foot being slidably mounted on the respective pin, and a spring-loaded locking mechanism, said mechanism being movable to create an opening for selectively receiving and locking said bag to said bottom member after said bag supporting foot passes into said aperture.

7. The assembly of claim 6 wherein said bottom member is formed with two apertures for receiving said feet.

8. The assembly of claim 7 wherein said apertures are open slots.

9. The assembly of claim 8 wherein said bottom member includes a plate with two lateral openings.
